RADIO SYSTEM

Application filed September 13, 1926. Serial No. 134,975.

My invention relates to communication systems, and more particularly to communication systems of the type in which high-frequency oscillations are guided along wire 5 conductors to convey intelligence or to convey energy for effecting the operation of electric signalling, controlling and communicating apparatus located at geographically separated points in the system.

10 One object of my invention is to provide a system wherein efficient communication may be maintained at a plurality of frequencies, one frequency being used for transmission from a given station and a different 15 frequency being employed for reception from distant stations.

Another object of my invention is to provide in a system of the type described, means whereby duplex communication may be 20 maintained without the necessity of changing the apparatus at any given station from the transmitting to the receiving state.

Another object of my invention is to provide, in a system of the type described, an 25 efficient antenna for phase-to-phase coupling, such antenna being provided with tuning means whereby it may be rendered simultaneously resonant to a plurality of frequencies.

Still another, and more specific object of 30 my invention, is to provide, in a wired-radio system, an antenna-coupling system comprising only two coupling conductors, instead of the usual three.

It is now well recognized that, in systems 35 utilizing power-lines as guiding channels for high-frequency currents, it is preferable to use phase-to-phase coupling instead of using the ground as the return conductor. It is not necessary, for the purpose of completely 40 disclosing my invention, to analyze the reasons for the superiority of phase-to-phase coupling, it being sufficient to note that it is desirable from the standpoint of efficiency.

In the past, it has been customary to use 45 two wires of a three-phase circuit for transmission, the third wire and the ground being utilized for reception. Obviously, this necessitated adding, at each station, three coupling antennæ to the poles already supporting the power-lines.

In many instances, it has developed that the line-supporting poles are not sufficiently strong to carry the weight of the additional coupling antennæ, and it has become desirable to reduce the number of such antennæ 55 to the lowest number compatible with efficient operation.

Obviously, to obtain the most efficient transfer of energy from the transmitting apparatus to the power lines, and from the power 60 lines to the receiving apparatus, it is necessary to employ coupling devices, tuned to the transmitting frequency on the one hand and to the receiving frequency on the other.

By my invention, I eliminate the antenna 65 or coupling condenser formerly employed for reception, by coupling both the receiving and sending apparatus to the power-lines through two antennæ or coupling condensers that are connected together and so tuned, 70 as a whole, to be resonant to both the transmitting frequency and the receiving frequency. In addition, I provide an arrangement whereby the transmitting frequency and the receiving frequency may be interchanged, 75 enabling the operator at any station to transmit on the frequency he formerly employed for receiving and to receive on the former transmitting frequency.

The novel features which I believe to be 80 characteristic of my invention are set forth with particularity in the appended claims. My invention itself, however, both as to its organization and method of operation, will best be understood by reference to the following description, taken in connection with the accompanying drawings, in which,

Fig. 1 is a diagrammatic view of a communication system according to my invention,

Fig. 2 is a diagrammatic view of a preferred form of my invention as applied to a single one of the transmitting-receiving stations illustrated in Fig. 1.

Referring specifically to Fig. 1, a plurality of metallic conductors 1, 2 and 3 that may be either power lines, telegraph lines, or the like, extend between a plurality of transmitting-receiving stations 4 and 5. The station 4 is provided with two coupling an-

5 antennæ, 6 and 7, while the station 5 is similarly equipped with two antennæ 8 and 9. These antennæ are electrostatically coupled to the power lines, being supported in proximity thereto on poles (not shown).

10 As illustrated in Fig. 2, the antenna 6 is connected, through a variable inductor 11, a tuned circuit, comprising an inductor 12 and a condenser 13, a portion 14 of the secondary 15 of a radio-frequency coupling-transformer 15, the primary of which is connected to the transmitting apparatus (not shown), to a grounded conductor 16. The antenna 7 is connected, through a variable inductor 17, a 20 tuned circuit comprising an inductor 18 and a condenser 19, a portion 21 of the secondary of the radio-frequency coupling-transformer 15, and a coupling inductor 22, to the grounded conductor 16. A circuit, comprising a 25 condenser 23, an inductor 24 and the armature 25 of a wave-change relay 26, is connected in shunt to the coupling inductor 22. A second inductor 27 is so arranged that it may be substituted for the inductor 24, upon actuation of the wave-change relay.

A certain capacity exists between the antennæ 6 and 7, this capacity being represented by a condenser 28.

30 An inductor 29, one end of which is connected to the grounded conductor 16, is connected to the antenna 7 through a variable condenser 31 shunted by a high resistance 32. The inductor 29 is inductively associated with the coupling inductor 22 for a purpose which 35 will be explained later.

35 A receiving set 33, comprising a coupling coil 34, and the necessary rectifying and amplifying apparatus, (not shown) is arranged to be energized by the coupling inductor 22. 40 The receiving apparatus may be grounded by a conductor 35, if desired, for stabilizing purposes.

The principle of operation of my invention 45 is based on the fact that a series resonant circuit and a parallel resonant circuit, each separately tuned to the same frequency, will, when connected in series, be resonant to, and have zero reactance at, two separate frequencies. One of these resonant frequencies 50 will lie above the frequency to which the separate circuits are tuned, and the other below.

The reactance of a series of resonant circuit is given by the formula

$$55 \quad X = \omega L_s - \frac{1}{\omega C_s},$$

where X equals the reactance, $\omega = 2\pi f$, L_s = the inductance of the circuit, and C_s = the capacitance associated therewith. The series circuit has zero reactance at the resonant frequency, when

$$60 \quad \omega L_s = \frac{1}{\omega C_s}.$$

At a lower frequency the capacity reactance 65 predominates, and this reactance is called

negative. At a frequency above resonance the inductive reactance is greatest, and the reactance in this case is called positive.

The reactance of a parallel resonant circuit is given by the formula

$$70 \quad X = \frac{\omega L_p}{1 - \omega^2 L_p C_p},$$

if the ohmic resistance of the circuit is neglected. Were it not for the resistance of the 75 circuit, the reactance would be infinite at the frequency which makes the term $1 - \omega^2 L_p C_p$ equal to zero. This frequency, is termed the resonant frequency. At frequencies below the resonant frequency, the reactance is positive, while, at frequencies above resonance, the reactance is negative.

80 When a series-resonant circuit and a parallel-resonant circuit are connected in series, the total reactance is the sum of the two separate reactances. By equating to zero the sum of the reactances, and solving for the frequency, two solutions will be found. Expressed algebraically, the equation

$$85 \quad \left(\omega L_s - \frac{1}{\omega C_s} \right) + \left(\frac{\omega L_p}{1 - \omega^2 L_p C_p} \right) = 0$$

90 is satisfied by two distinct and separate values of ω or, in other words, by two values controlled by the ratio of L_s , the series inductance, to L_p , the parallel inductance.

95 In order, therefore, to obtain an efficient transfer of energy from the transmitting set to the power lines at one frequency and an efficient transfer to the receiving set from the 100 power lines at another and different frequency, it is necessary that the coupling antenna be made resonant, in the manner described above, to these two frequencies.

105 Referring again to Fig. 1, a series circuit may be traced to include the condenser 28, the inductors 11 and 17, the radio-frequency coupling-transformer secondaries 14 and 21, and the inductor 22. A parallel resonant circuit comprises the inductors 12 and 18 and the condensers 13 and 19. The component parts of both the parallel and series-resonant circuits have been divided equally between the two antennæ, in order that the center 110 point therebetween may be grounded, and the current in each antenna may be made equal to that in the other.

115 The elements of the series and parallel circuits are so chosen that the two frequencies to which they are resonant, when considered as a whole, are the transmitting and receiving frequencies to be employed in the operation of the entire system.

120 The output from the transmitting set is fed into the coupling antennæ through the radio-frequency coupling-transformer and causes an oscillatory current in the circuit which includes the capacity between antenna 6 and antenna 7. Power is taken from the antennæ by the lines 1 and 2 by virtue of the 125 130

capacity coupling such lines to each antenna. This capacity is represented by condensers 37 and 38, in Fig. 1.

Energy received from a distant transmitting station is fed into the receiving set through the inductors 22 and 34, the coupling-antenna system being tuned to the receiving frequency, as explained previously.

In order that the locally generated transmitting frequency may be prevented from affecting the receiving set, the shunt circuit, including the condenser 23 and the inductor 24, is tuned to be series resonant to the transmitting frequency, and carries all, or nearly all, of the transmitting energy circulating in the antenna system.

In addition, the circuit including the resistance-shunted condenser 31 and the inductor 29 is so arranged that it induces a variable amount of energy at the transmitting frequency, and 180° out of phase therewith into the receiving apparatus 33. This balances out the voltage applied across the receiver due to the ohmic resistance of the shunt-circuit condenser 23 and inductor 24 or inductor 27, as the case may be.

Under certain circumstances, it may be desirable to transmit on the frequency normally used for receiving and to receive on the frequency normally used for transmitting. To accomplish this, a wave-change switch is provided which actuates a relay 26 to connect either of the shunting inductors 24 and 27 in the circuit. Appropriate changes are made, at the same time, in the tuned antenna circuits, in the adjustment of the receiving set and in the adjustment of the transmitting set. The instrumentalities for accomplishing these changes will be obvious to those skilled in the art, and are, therefore, not specifically shown or described.

The condenser 23 and the inductor 24 are tuned together to the normal transmitting frequency, while the shunt circuit, comprising the condenser 23 and the other inductor 27, is tuned to the normal receiving frequency. It is thus obvious that, when the appropriate inductor is connected in circuit by the wave-change relay armature 25, the frequency to which it is tuned will be bypassed and prevented from affecting the receiver 33.

It will thus be apparent that, by my invention, I am enabled to dispense with one of the coupling antennæ or coupling condensers formerly used in duplex transmission over metallic conductors, with no substantial loss in efficiency.

The use of the radio-frequency coupling-transformer to transfer the power from the transmitter to the tuned circuit has the advantage of materially reducing the interference caused by the radiation of harmonics.

Although I have described a certain specific form of my invention in detail, and have

pointed out the principle upon which it is based, I do not intend that the language of the following claims shall be limited to the precise features described, only such limitations being intended as are necessitated by the prior art.

I claim as my invention:

1. In a communication system, a plurality of conducting channels, an oscillation generator, an antenna coupled to each channel and fed by said generator, and means whereby said antennæ together constitute a single circuit simultaneously resonant to a plurality of frequencies.

2. In a communication system, a plurality of conducting channels, a transmitting set, a receiving set, an antenna coupled to each channel and to each of the transmitting and receiving sets, and means whereby said antennæ together constitute a single circuit that is resonant simultaneously to a plurality of frequencies.

3. In a communication system, a plurality of conducting channels, an oscillation generator, an oscillation detector, an antenna coupled to each channel, said antennæ being so connected together as to constitute a single circuit simultaneously resonant to a plurality of frequencies, and means for coupling said generator and said detector to both of said antennæ.

4. In a communication system, a plurality of conducting channels, means for generating oscillations, means including a plurality of antennæ constituting a single circuit resonant to a plurality of frequencies for introducing said oscillations into said channels, oscillation detecting means coupled to said antenna system, and means including a plurality of reactors, for preventing the generated oscillations from affecting the oscillation detecting means.

5. In a communication system, means for transmitting at one frequency, means for receiving at another frequency, said plurality of means mutually including a coupling device tuned simultaneously to both frequencies, and means whereby the transmitting and receiving frequencies may be interchanged.

6. In a communication system, means for transmitting at one frequency, means for receiving at another frequency, said plurality of means mutually including a coupling device tuned simultaneously to a plurality of frequencies, and means including an optionally selectable tuned shunt circuit whereby the transmitting and receiving frequencies may be interchanged.

7. In a communication system, a plurality of conducting channels, an antenna capacitively coupled to each channel, a connection between said antennæ including a parallel-resonant circuit and a plurality of inductors, the antennæ being so disposed that capacitive coupling exists therebetween, whereby the an-

tenna system is resonant to a plurality of frequencies, means for setting up oscillations at one of said frequencies in said antenna system, a receiving device coupled to one of said inductors, and a circuit series-resonant to said oscillations connected in shunt to the inductor to which said receiving device is coupled.

8. In a communication system, a plurality of antennæ so disposed as to be capacitively coupled to one another, a connection between said antennæ including a parallel-resonant circuit and a plurality of inductors, whereby said antennæ system is resonant to a plurality of frequencies, means for introducing oscillations at one of said frequencies into said antenna system, a receiving device coupled to one of said inductors for rendering apparent signals received by said antenna system at another of said frequencies, and means for at will by-passing around the inductor to which said receiving device is coupled, oscillations at either of said frequencies.

9. In a communication system, a plurality of conducting channels, a plurality of antennæ so disposed as to be capacitively coupled to one another and to said channels, a connection between said antennæ including a parallel-resonant circuit and a plurality of inductors, a source of oscillations coupled to said antenna system, a receiving device coupled to said antenna system, and means for preventing said oscillations from affecting said receiving device, said last-named means including a phase-adjusting device.

10. In a communication system, a plurality of conducting channels, a plurality of antennæ so disposed as to be capacitively coupled to one another and to said channels, a connection between said antennæ including a parallel-resonant circuit and a plurality of inductors, a source of oscillations coupled to one of said inductors, a receiving device coupled to another of said inductors, a series-resonant circuit connected in shunt to the inductor to which is coupled said receiving device, for by-passing therearound oscillations at the frequency to which said circuit is tuned, and additional means for preventing said oscillations from affecting said receiving device.

In testimony whereof, I have hereunto subscribed my name this 7th day of September, 1926.

55 CLARENCE A. BODDIE.
